MACHINE FOR ARMING BOMB FUSES

Margaret J. Ferrone, Boonton, and Clyde W. Burdge, Hackettstown, N. J.

Application January 30, 1943, Serial No. 474,214

6 Claims. (Cl. 73—51)

(Granted under the act of March 3, 1883, as amended April 30, 1928; 370 O. G. 757)

The invention described herein may be manufactured and used by or for the Government for governmental purposes without the payment to us of any royalty thereon.

This invention relates to a machine for testing the arming movements of bomb fuse vanes.

The first object is to provide means whereby the introduction into the machine and the removal therefrom of the fuse, will be greatly facilitated.

Another object is to provide an indicator in association with a propeller, to accurately indicate the number of revolutions of the propeller and thereby indicate the number of revolutions of the bomb propeller necessary to arm the bomb, and to provide an index which, after being moved in relation to an appropriate scale, may be quickly returned to normal position to be ready to operate in the arming of the next fuse.

According to the old method heretofore employed, a propeller vane was mounted directly on the fuse with wire fingers transmitting the revolutions of the vane to an indicator. The means we employ is much simpler to accomplish the same purpose, and much more efficient and effects a much greater saving of time than possible with the old devices.

In the present embodiment of the invention, the part of the fuse operated upon is the part that revolves with the vanes of the bomb propeller in the flight of the bomb and one of the parts through which the arming wire is threaded, the other wire receiving part being carried by a non-rotating part of the bomb. The number of revolutions required to set the internal mechanism of the fuse for arming, which is a known factor, will be indicated on the scale, conveniently visible to the operator.

In the drawing, Figure 1 is a front elevation of the machine.

Figure 2 is a central longitudinal section in a direction diagonally opposite to Figure 1.

Figure 3 is a section taken on the line 3—3 of Figure 1, showing the removable pointer-carrying nut and its relation to the scale plate.

Referring to the drawing, the numeral 1 designates the base of the machine upon which is mounted a standard 2, provided at its upper end with a bracket 3, and with a similar bracket 4 intermediate its length. Each bracket supports a ball bearing assembly. The upper bracket assembly is contained in an apertured enlargement 5, which may be integral with the bracket or secured thereto by suitable means. The enlargement is bored as at 5' to receive a disk 6 supported on ball bearings 7 on the floor of the bore. The upper portion of the enlargement is threaded to receive a threaded closure cap 7', between which and the disk are ball bearings 8.

The cap and disk are centrally apertured for the passage of the threaded rod 9, the upper end of which has a bearing in the cap, the rod being pinned to the disk for joint rotation.

5 The intermediate bracket 4 supports an enlargement very similar to the one just described, and comprises a centrally apertured enlargement 10, bored to receive the disk 11, like the disk 6, supported on the floor of bore 12 by ball bearings 13, there being an apertured cap 14 threaded upon the upper part of the enlargement.

The lower unthreaded part 15 of the rod 9, is somewhat larger in diameter than the upper part, and the disk 11, like the disk 6 is pinned to the rod, the arrangement being such that the rod and all the parts, presently to be described, are supported in anti-friction manner by the two disks.

Below the enlargement 10, a propeller 16 is secured to the rod, and below the propeller the rod 20 is provided with a groove 17 which receives the end of a screw 18 in the sleeve 19 of the hollow-head 20 which envelopes the end of the fuse, as shown in Figure 2, the head being limited in its downward movement by a solid head 21, integral with the rod.

25 The fuse receiving head is provided with oppositely disposed recesses 22, which receive the arming wire strip 23, carried by the rotatable part of the fuse, so that when the head is rotated with the rod 9, the strip will rotate with it, the head, as has been mentioned, being keyed to the rod by the screw and groove connection.

30 A vise 24 is supported on the base 1 in front of the standard and directly below the mechanism that has been described, and its jaws 25 and 26 are shaped to grip the lower part of the fuse when it is being operated upon. The front jaw 25 is fixed, it being secured to a bracket 27, fastened to the base. About centrally of the fixed

35 jaw is a fuse table 28, to the under side of which a bearing 29 is provided for the horizontal arm 30 of a crank or operating arm 31. Fixed to the arm 30 is a cam 32 received in the fork 33 of a member 34 attached to the removable jaw of the vise, the fit of the cam in the fork being such that the crank operating arm 31 if slightly rocked in one direction or the other, the vise jaw 26 will be moved to either grip or release the fuse, as the requirements of the operation may dictate.

40 A guide 35 is secured to the vertical portion of the jaw 25 and may extend through an opening in the movable jaw, for the obvious purpose of guiding the jaw.

45 An important feature of the invention is the means by which the number of revolutions of the rod 9 is determined at a glance. This means comprises an elongated graduated scale plate 36, secured by screws 37 and 38, to the enlargements 5 and 10, the plate being provided with a nar-

row slot 39 for the passage of a pointer 40, whose inner end is secured to one jaw of a two-part nut 41. This nut comprises jaws 41' hinged together as at 42, each jaw being chamfered as at 43, to enable the jaws to be rocked apart when the hand grips 44, one of which is attached to each jaw, are pressed toward each other against the pressure of the spring 45. A semi-circular internally threaded recess 46 is in each jaw, and the threads of one recess are a continuation of the threads in the companion recess, and these threads are of the same pitch as the threads on the rod 9, so that when the rod is rotated by the means presently described, the nut will be fed up the rod, indicating by the pointer, as the nut rises, the number of revolutions of the rod, and informing the operator when the fuse elements have been sufficiently rotated.

Rod 9 is rotated by the propeller acted upon by compressed air which may be derived from any suitable source and under any suitable degree of pressure and control, and we do not limit ourselves to any particular arrangement by which the air is controlled and supplied to the propeller. One way by which this may be accomplished is through a pipe 47 communicating with a duct 48, and connecting with a number of downwardly directed orifices in the bottom of the enlargement 10.

In operation, a fuse is placed upon the table 23 and clamped in the vise by rocking the operating arm 31, the head 20 having been raised by the operator sufficiently to admit the fuse. The head is lowered until the fuse arming strip 23 is received in the recesses 22. The propeller is then rotated by a compressed air current which rotates the rod 9, thereby rotating the rotatable part of the fuse. The rotation of the rod meanwhile feeds the nut 41 upwardly on the rod, the nut and pointer moving in relation to the graduations on the scale plate, and when the pointer reaches a predetermined point, the movement of the rod is arrested. The operator will then release the threaded jaws of the nut from the rod by separating the jaws, when the nut may be returned to a seat on the cap 14, and the pointer to its low point on the scale.

We claim:

1. In a machine of the character described, in combination, means for supporting a fuse, a rotatable rod and means for rotating it, a fuse receiving member slideable on the rod and keyed thereto for rotation therewith, index means carried on the rod, connections between the rod and the index means whereby said means is moved longitudinally of the rod when the rod is rotated, a calibrated indicator scale cooperating with the index means to measure the number of revolutions of the rod, and means carried by the fuse receiving head for operative engagement with an element carried by a rotatable part of the fuse.

2. In a machine of the character described, in combination, means for supporting and stabilizing a fuse, a rotatable rod, a propeller fixed on the rod for rotating it, a fuse receiving member slideable on said rod and keyed thereto for rotation therewith, index means carried by the rod, connections between the index means and rod whereby the index means is moved longitudinally of the rod when the rod is rotated, a calibrated indicator scale cooperating with the index means

to measure the number of rotations of the rod, and means carried by the fuse receiving head for operative engagement with an element carried by a rotatable part of the fuse.

3. In a machine of the character described, in combination, means for supporting and stabilizing a fuse, a rotatable rod threaded in part, a propeller fixed to the rod, means for rotating the propeller and thereby the rod, a fuse-receiving head slideable on said rod and keyed thereto for rotation therewith, a nut adapted to coat with the threads of the rod, the nut comprising hinged jaws each of which is provided with a semi-circular internally threaded recess, the threads of one jaw being a continuation of the threads of the companion jaw, the nut threads being of a pitch to coat with the threads on the rod, means for opening the jaws to disengage their threads from the threads of the rod to permit the nut to be manually returned to normal position, a pointer carried by the nut, a calibrated plate cooperating with the pointer to indicate the number of revolutions of the rod, and means carried by the fuse-receiving head for operative engagement with a rotatable part carried by a fuse.

4. In a machine of the character described, in combination, a standard having upper and lower laterally extending brackets, a rod supported by and rotatably mounted in said brackets, a part of the rod between the brackets being threaded, means for rotating the rod, a nut seated on the lower bracket and having threads coating with the threads of the rod and provided with a pointer, a calibrated indicator plate secured to the brackets and cooperating with the pointer to measure the number of revolutions of the rod as the nut traverses the rod, means for manually releasing the nut from the rod to permit it to be returned to normal position independently of the rod, and a hollow fuse-receiving head slideable on the rod and keyed thereto for rotation therewith, the head being provided with means for operative engagement with an element carried by a rotatable part of a fuse.

5. The invention according to claim 2, characterized in that the means for supporting and stabilizing the fuse comprises a vise having a fuse supporting table between its jaws.

6. In a machine for determining the extent of the threaded relation of threaded members to be tested, a rotatable threaded rod, bearings for the rod, a head on the rod bored to receive one of said members, the head being slidably mounted on the rod and keyed thereto for joint rotation, means for rotating the rod, a nut comprising hinged jaws, each jaw provided with an internally threaded recess, the threads in one jaw being a continuation of the threads in the companion jaw and in coordination with the threads of the rod, means carried by the jaws to facilitate the manual separation of the jaws to enable the nut to be moved on the rod independently of the rod threads, a pointer carried by the nut, a calibrated indicator scale cooperating with the pointer to indicate the number of revolutions of the rod, and means carried by the head for operative engagement with the one of said members to be received by the head.
